UNITED STATES PATENT OFFICE.

EARL L. PETERSON, OF CORONA, NEW YORK, ASSIGNOR TO UNITED CONCRETE PIPE COMPANY, OF NEW YORK, N. Y., A CORPORATION OF DELAWARE.

DIFFUSION OUTLET FOR CONDUITS.

Application filed August 10, 1920. Serial No. 402,643.

To all whom it may concern:

Be it known that I, EARL L. PETERSON, a citizen of the United States of America, residing at Corona, in the county of Queens, 5 Long Island, and State of New York, have invented certain new and useful Improvements in Diffusion Outlets for Conduits, of which the following is a specification.

My invention relates to diffusion outlets 10 for conduits, and particularly to an outlet cover or guard, which not only lessens danger of stoppage, but also aids in effecting discharge from the conduit. The invention is particularly applicable to submerged 15 sewer pipe outlets.

In the accompanying drawings—

Fig. 1 is a side elevation of a diffusion block in which my invention is embodied in one form;

20 Fig. 2 is a broken plan thereof;

Fig. 3 is an end elevation of a pipe showing the diffusion block applied thereto;

Figs. 4, 5 and 6 are similar views of a modified construction;

25 Figs. 7, 8 and 9 are similar views of a further modification;

Figs. 10, 11 and 12 are similar views of another modification;

30 Fig. 13 is a longitudinal section through portion of a pipe showing a diffusion block in position thereon;

Fig. 14 is a section on the line 14—14, Fig. 13; and

Fig. 15 is a broken plan view thereof.

35 It is a frequent practice for municipalities to pipe their sewage to a neighboring body of water, such as a river, tidal basin, etc., and to discharge the sewage into the latter through ports formed at intervals in the

40 length of the sewer pipe. Often objects suspended in the water of submergence become lodged in the outlet openings of the conduit and block discharge therefrom. It requires constant inspection of the line to keep the

45 openings free from this trouble. The object of the present invention is to provide a diffusion block adapted to be arranged at such ports and serving not only to prevent stoppage thereof, but also to deflect the flow of

50 the water of submergence past the opening so as to assist in the discharge of the sewage from the pipe. While I have referred to submerged sewers as the type of construction to which the invention is particularly appli-

cable, it will be understood of course that the 55 construction may be used in many other installations to advantage, and I do not limit its application, therefore, to sewer pipe.

Referring to the constructions shown in Figs. 1 to 3, the conduit 20, through which the liquid to be discharged flows, is indicated as made from concrete, and has a peripheral port 21 formed therein through which the liquid escapes. In order to prevent, as far as possible, the retention of any 60 solids at the mouth of the port, its margin is rounded, as at 22, to afford a smooth passageway. As will be noted from Fig. 2, the port is here shown as substantially rectangular in plan. Covering this opening is a 65 diffusion block 23, which, where the conduit is of concrete, may similarly be molded from concrete, and its concave seat 24 may be set in grout on the pipe 20, to assist in holding it in position. I have provided also a pair of steel bands 25, which pass beneath the conduit and over the block, where they are drawn tight by bolts 26 engaging the angle iron ends 27. The block thus forms an arch, 70 which overlies the port 21 and affords lateral discharge openings 28 at right angles to the axis of the pipe. Cast integral with the block at its opposite ends, in the direction of the length of the pipe, are deflecting 75 plows or vanes 29 and 30. Where the pipe 80 is submerged in water which flows in opposite directions, as in a tidal basin, the vanes 29 and 30 deflect the current and divert it outward so that at the discharge ports the 85 flow past the outlet is at an angle to the axis of the pipe. This not only tends to keep any suspended matter in the water of submergence away from the aperture, but also exerts a certain suction effort which aids in discharging the contents of the conduit. 90

Where the conduit is located in a stream, where the direction of flow is always in one direction, the diffusion block may have but a single deflecting vane, pointed up-stream, as illustrated in Figs. 4, 5 and 6. In this case I have shown the discharge port in the pipe as circular, and the diffusion block is preferably located with its up-stream end wall adjacent the up-stream side of the discharge port. The margins of discharge port 100 105 31 are outwardly flared to prevent clogging.

In Figs. 7, and 8 and 9, I have shown another modified construction in which the

diffusion block has its discharge opening 32 arranged at the down stream end of the block in the direction of the flow of the current. The discharge port 33 in the conduit is flared at its outer margin only, to assist in maintaining the aperture clear.

In Figs. 10, 11 and 12 the conduit is provided with a pair of discharge openings 34 and 35, which open to a corresponding pair 10 of channels 36 and 37 diverging from the axial line of the pipe and opening to the sides of the diffusion block. Obviously, the same effect is obtained in this construction as in that first described by reason of the 15 current-deflecting vane 29 at the up-stream end of the diffusion block.

In all of the constructions, I have indicated small holes 38 in the blocks to facilitate their manipulation during manufacture 20 and adjustment in position on the conduit.

Various other modifications in construction and arrangement of apertures and discharge channels will readily occur to those skilled in the art which obtain substantially 25 similar results, without departing from what I claim as my invention.

I claim—

1. For use with a submerged conduit having a discharge port in its crown, a diffusion block 30 adapted to be arranged over the port and shaped to deflect the water of submergence into an outwardly directed current, and having a lateral discharge aperture communicating with the conduit 35 port and leading the discharge therefrom toward said outwardly directed current in the water of submergence.

2. For use with a submerged conduit having a discharge port, a diffusion block 40 adapted to be arranged over the port and having a lateral discharge aperture communicating with said port, said diffusion block being independent of the conduit and having associated means embracing the conduit 45 for securing the same in position over the discharge port in the conduit.

3. For use with a submerged conduit having a discharge port, a diffusion block 50 adapted to be arranged over the port and having a lateral discharge aperture communicating with said port, together with projecting end vane means for deflecting the liquid of submergence away from the outlet of the diffusion block.

55 4. For use with a submerged conduit having a peripheral port, a diffusion block having an arcuate seat adapted to rest on the conduit, an outwardly flared lateral discharge outlet from the diffusion block, and

a passage establishing communication between said outlet port in the conduit. 60

5. A diffusion block of the type described having a passage adapted to be placed in register with a peripheral port in a conduit on which the block is adapted to be seated, 65 a lateral discharge outlet to which said passage opens, and a deflecting nose at an end of the block and extending in the direction of the pipe length.

6. The combination with a conduit submerged in a flowing body of water, and having a peripheral port, of a diffusion block seated on said conduit at said port and having a lateral outlet, together with a deflecting nose for said diffusion block, said nose 70 being pointed up-stream, and serving to cause the water of submergence to be laterally deflected at the block for the purpose specified. 75

7. For use with a submerged conduit having a discharge port, a diffusion block adapted to be arranged over the port and having a lateral discharge aperture communicating with said port and opening to the water of submergence at a point above 80 the crown of the pipe. 85

8. For use with a submerged conduit having a discharge port, a diffusion block adapted to be arranged over the port and having a lateral discharge aperture communicating with said port and extending in a direction substantially parallel to the transverse horizontal axis of the pipe. 90

9. For use with a submerged conduit having a discharge port, a diffusion block 95 adapted to be arranged over the port and having a lateral discharge aperture communicating with said port, said block being shaped to deflect the flow of the water of submergence past the port away from said 100 aperture but in the general direction of the flow of said water of submergence to produce a suction effort aiding the discharge from said aperture.

10. For use with a submerged conduit 105 having a discharge port, a diffusion block adapted to be arranged over the port and having an outwardly flared lateral discharge aperture communicating with said port, said diffusion block having a V-shaped 110 plow end serving to deflect the flow of the water of submergence past said aperture in a direction to exert a suction effort at the aperture for the purpose specified.

In testimony whereof I have signed my 115 name to this specification.

EARL L. PETERSON.
